CLAIM

The ornamental design for a guitar neck support, as shown.

DESCRIPTION

FIG. 1 is a top perspective view of a guitar neck support; FIG. 2 is a bottom perspective view thereof;

FIG. 3 is a top plan view thereof;

FIG. 4 is a right side elevational view thereof;

FIG. 5 is a rear elevational view thereof; and,

FIG. 6 is a bottom plan view thereof.

The left side elevational view thereof is an identical, mirror-image of FIG. 4, and is, therefore, not illustrated here. Also, the front elevational view thereof is an identical, mirror-image of FIG. 5, and is, therefore, not illustrated here.

1 Claim, 3 Drawing Sheets
